UNITED STATES PATENT OFFICE.

EDWARD BORNHOEFT, OF NEW YORK, N. Y.

PIANO-PEDAL.

No. 820,622.

Specification of Letters Patent.

Patented May 15, 1906.

Application filed January 23, 1906. Serial No. 297,413.

To all whom it may concern:

Be it known that I, EDWARD BORNHOEFT, a citizen of the United States, residing at New York city, Bronx, county and State of New York, have invented new and useful Improvements in Piano-Pedals, of which the following is a specification.

This invention relates to an improved piano-pedal which can be readily tightened up from time to time and may be readily removed and replaced when worn or broken.

In the accompanying drawings, Figure 1 is a side view of my improved pedal, showing the piano-case in section. Fig. 2 is a plan, and Fig. 3 a vertical longitudinal section on line 3 3, Fig. 2.

The letter *a* indicates the bottom of the piano-case, of which *a'* is the front, having the removable panel *a''*. Through the front *a'* extends the pedal-foot *b*, engaged by the rod or lifter *c*. The rear end of foot *b* is provided with laterally-extending trunnions *b'*, journaled in the bearings *d'* of a slotted block *d*. This block is secured to the bottom *a* by means of screws *e* passing through laterally-projecting perforated flanges *d''* of the block. The slotted cap or cover *f* of block *d* is pro-

vided with a tailpiece *f'*, fulcrumed at *f''* to uprights *d''* of block *d*. Through a tapped perforation of tailpiece *f'* passes a set-screw *g*, engaging with its lower end a rest *d''*, formed on block *d* back of uprights *d''*.

By manipulating screw *g* the frictional contact between trunnions *b'* and their bearings may be readily adjusted. In case the foot *b* is to be removed or replaced the cap *f* is by screw *g* raised sufficiently to release trunnions *b'*, access to the screw being gained by first removing panel *a''*.

What I claim is—

In a piano-pedal, the combination of a pedal-foot having a trunnion with a slotted block having a trunnion-bearing, a pair of uprights, and a rest back of the uprights, and with a slotted cap pivoted to the uprights, and a set-screw tapped into said cap and engaging the rest, substantially as specified.

Signed by me at New York city, Manhattan, N. Y., this 22d day of January, 1906.

EDWARD BORNHOEFT.
